UNITED STATES PATENT OFFICE.

CHARLES B. MILLER, OF PHILADELPHIA, PENNSYLVANIA, ASSIGNOR TO
GEORGE MILLER & SON COMPANY, OF SAME PLACE.

DESIGN FOR A TOY FORT.

SPECIFICATION forming part of Design No. 34,354, dated April 9, 1901.

Application filed March 9, 1901. Serial No. 50,527. Term of patent 3½ years.

To all whom it may concern:

Be it known that I, CHARLES B. MILLER, a citizen of the United States, residing in Philadelphia, Pennsylvania, have invented and produced a certain new and original Design for a Toy Fort, of which the following is a specification.

My design for a toy fort is fully illustrated in the accompanying drawing, which represents the fort in perspective.

The essential feature of the design is the representation of a quadrangular stonework fort.

A represents the main building of a fort, and B is an upward extension at the front thereof.

a represents buttresses at the corners of the

building. In each side are openings c, and around the upper edges of the portion A is a battlement b of the "Walls of Troy" type. 20 Battlements b' also extend along the upper edge of the extension B.

I claim—

The design for a toy fort as herein described and as illustrated in the accompanying draw- 25 ing.

In testimony whereof I have signed my name to this specification in the presence of two subscribing witnesses.

CHAS. B. MILLER.

Witnesses:

ANNA HYNSON,
C. F. WOODWARD.
